(57) **CLAIM**

We claim the ornamental design for microphone holder, as shown and described.

DESCRIPTION

FIG. 1 is a front elevational view of the microphone holder; FIG. 2 is a rear elevational view of the microphone holder; FIG. 3 is a top plan view of the microphone holder; FIG. 4 is a bottom plan view of the microphone holder; FIG. 5 is a right side elevational view of the microphone holder; FIG. 6 is a left side elevational view of the microphone holder; FIG. 7 is a perspective view of the microphone holder; FIG. 8 is a perspective view of the microphone holder shown in FIG. 7, where movable parts have been moved outwardly and the lock handle on the top has been rotated in a clockwise direction; and,

FIG. 9 is a perspective view of the microphone holder in use, including an unclaimed microphone which forms no part of the claimed design.

The broken line portion of the figure drawings is included to show unclaimed subject matter only and forms no part of the claimed design.
